UNITED STATES PATENT OFFICE.

LOUIS F. THIEL, OF CHICAGO, ILLINOIS.

ENVELOP-FASTENER.

1,277,156.

Specification of Letters Patent. Patented Aug. 27, 1918.

Application filed March 26, 1917. Serial No. 157,549.

To all whom it may concern:

Be it known that I, LOUIS F. THIEL, a citizen of the United States, and a resident of the city of Chicago, in the county of 5 Cook and State of Illinois, have invented certain new and useful Improvements in Envelop-Fasteners; and I do hereby declare that the following is a full, clear, and exact 10 description of the same, reference being had to the accompanying drawings, and to the numerals of reference marked thereon, which form a part of this specification.

This invention relates to an improved 15 form of locking envelop, and more particularly to the fastening or locking means of the envelop whereby the envelop may be unreleasably locked in closed position, thereby producing an envelop permitting access to the interior of the same after it has been 20 closed only by destroying the fastening means or the envelop itself, thus affording a means for sending documents, papers, or other things adapted to fit within an envelop without having the same interfered 25 with before the delivery thereof to the proper person for whom they were intended.

It is an object of this invention to construct a locking envelop adapted to be opened, after the same has been closed, only 30 by destroying the envelop.

It is also an object of this invention to provide an envelop having interfitting means thereon adapted to unreleasably engage one another to lock the envelop.

Another object of this invention is the 35 construction of an envelop provided with means on the back thereof adapted to engage a means on the envelop flap to hold the envelop permanently locked.

It is furthermore an object of this invention 40 to construct hooked locking means for an envelop adapted to lockingly engage a means on the envelop flap to permanently hold the envelop locked.

It is an important object of this invention 45 to provide a locking means for an envelop, simple and inexpensive of construction, adapted to permanently hold the envelop locked.

Other and further important objects of 50 this invention will be apparent from the disclosures in the drawings and specification.

The invention (in a preferred form) is 55 illustrated in the drawings, and hereinafter more fully described.

On the drawings:

Figure 1 is a rear elevational view of a closed envelop, having a locking means thereon embodying the principles of this 60 invention.

Fig. 2 is a section taken on line 2—2 of Fig. 1.

Fig. 3 is an enlarged fragmentary vertical section taken through the locking means of 65 the envelop, with the locking parts in initial position.

Fig. 4 is a similar section showing the next step in the locking operation.

Fig. 5 is a similar section showing the 70 locking parts engaging one another.

Fig. 6 is a section similar to that shown in Fig. 3, but showing the parts permanently locked to prevent opening of the 75 envelop.

Fig. 7 is a plan view of the flap opened.

As shown on the drawings:

The reference numeral 1, designates the front sheet of an envelop, made of heavy 80 paper, cloth or other suitable material, having integrally formed on each end thereof a rear side flap 2, each of which is bent inwardly along its integral edge of lie flat against the inner surface of the front sheet 85 1. Also integrally formed on the front sheet 85 at the lower edge thereof is a back piece 3, bent inwardly to lie flat against the side flaps 2, and is rigidly secured thereto by glue or other suitable means to form the body of 90 the envelop. The upper edge of the back 95 piece is parallel to the base of the envelop and has integrally formed thereon a short distance from each end thereof a rearwardly or outwardly directed hook or male locking member 4.

Integrally formed along the upper edge 100 of the front sheet 1, is a top flap 5, bent rearwardly and downwardly, and then inwardly and upwardly upon itself to form a locking flap 6, provided with a notch or opening 7, near each end thereof aligned 105 with one another and adapted to register with the hooks 4, when the locking flap 6, is down. Glued or rigidly secured longitudinally across the inner surface of the top flap 110 5, is a reinforcing strip 8, having integrally formed near each end thereof, a downwardly directed lug or latch member 9, each of which is bent away from said top flap 5, toward the locking flap 6, to form a latch or tongue adapted to lie opposite one of the openings 7.

The operation is as follows:

In the form of the device shown in Figs. 1 to 6, inclusive, after the body of the envelop has been filled with papers or documents to be mailed or expressed, the top flap is bent toward the back piece 3, of the envelop into a position wherein the openings 7, of the locking flap 6, register with the hooks 4, as shown in Fig. 3. The hooks are then forced through said openings into a position in which the hooks contact or rest against the latches 9, as shown in Fig. 4. The back piece 3, is now pulled down, thus forcing the hooks 4, to springingly engage below the lower ends of the latches 9, as shown in Fig. 5. By pulling the back piece 3, down farther, the upper bent portions of said hooks seat upon the lower edges of said openings 7, as shown in Fig. 6, thus permanently locking the envelop, and permitting the contents of the envelop to be removed only by destroying the envelop or the locking means thereof. This permanent locking is due to the fact that when the fastening means for the envelop are in the position shown in Fig. 6, the hooks are prevented from moving upwardly by the latches 9, which engage in said hooks, thereby making it impossible to withdraw the locking hooks through the openings 7, when once they have been moved into locking position.

I am aware that various details of construction may be varied through a wide range without departing from the principles of this invention, and I therefore do not purpose limiting the patent granted otherwise than necessitated by the prior art.

I claim as my invention:

1. In a device of the class described an en-

velop body, a locking member integral with the body, a double flap member, one member having apertures therein through which the locking members are adapted to be inserted and hooks secured to the other flap member to engage said locking members. 40

2. A locking envelop comprising a front sheet, end and back sheets, hooks formed integral with the back sheet at the upper edge thereof, a folded flap having apertures to receive the hooks therethrough, and a reinforcing strip secured to the flap having integral downwardly directed lugs, each lug shaped at its lower end to form a tongue to engage the respective hook. 45

3. In a device of the class described, an envelop body having overlapping parts, a locking member on one of the parts, the other part having a doubled portion with an aperture therein through which the locking member is adapted to be inserted, and a shiftable latch within the doubled portion adapted to engage the said locking member. 55

4. A locking envelop having overlapping parts, a locking member on one of said parts having a plurality of reversely hooked portions, the other part having a doubled portion provided with an intermediate space, and a movable part within the doubled portion adapted to engage the hooked locking member. 60

In testimony whereof I have hereunto subscribed my name in the presence of two subscribing witnesses.

LOUIS F. THIEL.
